United States Patent Office.

JOSEPH MOORE, OF TARENTUM, PENNSYLVANIA.

Letters Patent No. 94,020, dated August 24, 1869.

IMPROVED SPRING-BED BOTTOM.

The Schedule referred to in these Letters Patent and making part of the same.

To all whom it may concern:

Be it known that I, JOSEPH MOORE, of Tarentum, in the county of Allegheny, and State of Pennsylvania, have invented a new and improved Spring-Bed Bottom; and I do hereby declare that the following is a full, clear, and exact description thereof, which will enable others skilled in the art to make and use the same, reference being had to the accompanying drawings, forming part of this specification.

This invention relates to improvements in spring bed bottoms, having for its object to provide more yielding bottoms than any now in use.

The invention consists in supporting the longitudinal spring-bars upon transverse bars, one near each end, which are suspended by spring-followers, enclosed in suitable cases, in the said cross-bars, and connected by straps to the frame of the bedstead, in such a way that the followers work out and in, in connection with long elastic springs as the pressure varies, all as hereinafter more fully specified.

Figure 1 represents a transverse section of my improved spring-bed frame, taken through one of the transverse supporting-bars, and

Figure 2 represents a longitudinal section of the same.

Similar letters of reference indicate corresponding parts.

A represents the common longitudinal slats; and B, the transverse supporting-bars.

These are provided with spring-followers C, enclosed in a case, D, and connected to straps E, suspended by hooks to the frame of the bed, and working under friction-rollers F, at the ends of the bars B.

The said followers are provided with long spiral springs G, which may have any amount of play or movement, and thus be more elastic and flexible than when made shorter, or arranged in positions necessarily confined. The said springs are contracted under the weight of the load, and expanded when the load is removed.

Having thus described my invention,

I claim as new, and desire to secure by Letters Patent—

The combination of the longitudinal spring-bars A, transverse bars B, spring-followers C, straps E, and friction-rollers F, substantially as specified.

JOSEPH MOORE.
